Specification for Design.

Patented July 4, 1922.

Application filed March 11, 1922. Serial No. 1,131. Term of patent 14 years.

To all whom it may concern:

Be it known that I, DUDLEY FREEMAN, a citizen of the United States, residing at Roxbury, in the county of Suffolk and Commonwealth of Massachusetts, have invented a new, original, and ornamental Design for a Sole or Tap, of which the following is a specification, reference being had to the accompanying drawing forming a part thereof.

Figure 1 of the drawing is a plan view;

Fig. 2 is a section taken on the line 2—2, Fig. 1; Fig. 3 is a section taken on the line 3—3, Fig. 1; Fig. 4 is a section taken on the line 4—4, Fig. 1; and Fig. 5 is a section taken on the line 5—5, Fig. 1, showing my new design.

I claim:

The ornamental design for a sole or tap as shown.

DUDLEY FREEMAN.
